UNITED STATES PATENT OFFICE.

JAMES M. CARRICO AND WILLIAM G. CARRICO, OF TOWSON, MARYLAND.

SPIGOT.

SPECIFICATION forming part of Letters Patent No. 660,210, dated October 23, 1900.

Application filed January 22, 1900. Serial No. 2,392. (No model.)

To all whom it may concern:

Be it known that we, JAMES M. CARRICO and WILLIAM G. CARRICO, citizens of the United States, residing at Towson, in the county of 5 Baltimore, State of Maryland, have invented certain new and useful Improvements in Spigots, of which the following is a specification, reference being had therein to the accompanying drawings.

10 This invention relates to spigots, and particularly to a valve-stem packing for a spigot having a reciprocating valve.

The invention has for one object to provide improved means for compressing a packing-block into contact with the cap and the valve-stem of a spigot when the valve is opened, and thus preventing the leakage which occurs about such a stem from the pressure of water passing through the spigot.

15 A further object of the invention is to support such a packing in position when the valve is closed and to gradually increase the pressure on the packing as the valve is opened and the water admitted to the discharge-pipe.

20 Other objects and advantages of the invention will hereinafter appear in the following description, and the novel features thereof will be particularly pointed out in the appended claims.

25 In the drawings, Figure 1 is a vertical section through a spigot with the valve closed. Fig. 2 is a horizontal section on the line 2-2 of Fig. 1. Fig. 3 is a perspective of separated parts of the valve and the packing for 30 its stem, and Fig. 4 is a detail vertical section illustrating the stem-packing under compression.

Like letters of reference indicate like parts throughout the several figures of the drawings.

35 In the present application of the invention the valve is shown as applied to a spigot or faucet A, having an inlet-pipe A¹ and discharge-pipe A², connected by a valve-seat A³; but it will be understood that the valve-stem packing may be applied in any other desired form of device for controlling the flow of liquid.

40 In the form of spigot illustrated in Fig. 1 a chamber A⁴ is provided above the valve-seat, and through this chamber a valve-stem B extends and is provided at its projecting

end with a suitable handle B', while its lower portion is provided with suitable threads B², adapted to engage the interiorly-threaded 55 aperture C', formed in the valve-holder C. This holder carries at its lower portion a conical valve C², adapted to fit the seat A³, and the holder has at its opposite sides guide-wings C³, adapted to travel in grooves A⁵, 60 formed in the valve-casing A. These wings prevent the rotation of the valve and cause the same to reciprocate in a vertical line if the handle be rotated.

The parts hereinbefore described may be 65 of any preferred details of construction.

Above the valve-holder C an interiorly-threaded compressor D is located and through which the threaded portion B² of the stem B extends. This compressor is provided with 70 wings D', traveling in the grooves A⁵ to prevent the rotation thereof and cause a vertical movement of the compressor simultaneously with the movement of the valve C². Resting upon the upper face of this compressor D is 75 a suitable coil or other form of spring E, having at its upper face a washer F, and upon this washer a compressible packing-block G, preferably conical in form, is located and provided with a central aperture G', through 80 which the stem B passes. This packing may be of rubber or any desired material and is adapted to fit the inner face of a cap A⁶, threaded or otherwise secured to the valve-casing A. The stem B is also provided with 85 a shoulder B³ above said packing to prevent longitudinal movement of the stem when operating the valve and compressor. It will also be apparent that the grooves A⁵ extend downward from the top of the casing, so as 90 to permit the valve-holder and compressor to be placed in position or readily removed therefrom and held against rotary movement, so as to be simultaneously reciprocated.

From the foregoing description it will be 95 apparent that a rotation of the valve-stem B in the proper direction will open the valve C², permitting the pressure of water to enter the discharge-pipe A² and simultaneously raise the compressor D and place under compression the packing G through the medium of the spring E, thus by lateral expansion making a tight joint about the stem B and preventing all leakage at that point. When

the valve is in the closed position, as shown in Fig. 1, the spring E sustains the packing in position and by bearing against the under face of the shoulder B³ prevents any downward movement thereof. A collar B⁴ may be provided to prevent downward movement of the stem when opening the valve. It has been found that if the stem be packed sufficiently tight to prevent leakage the operation of the valve is rendered difficult and the parts quickly wear so as to cause leakage and necessitate repairs. With the present structure the valve-stem can easily be rotated and the packing is not compressed until the pressure of water enters the discharge-chamber, and such tight packing is necessary to prevent leakage. The structure therefore effects a tight joint at the necessary time and permits at other periods a free and easy rotation of the stem to effect the operation of the valve. A further material improvement is the application of this packing to a valve which reciprocates vertically toward and from its seat and is not given a rotary movement, which tends to wear and quickly destroy the valve.

It is obvious that changes may be made in the details of construction and configuration of the several parts without departing from the spirit of the invention as defined by the appended claims.

Having described our invention, what is claimed is—

1. In a valve-casing, the combination of a reciprocating valve held against rotation, a threaded stem for operating the same, a compressor threaded upon said stem and held

against rotation, a conical packing-block surrounding said stem and expanded laterally in the reciprocation of said compressor, and a cap surrounding said packing; substantially as specified.

2. In a valve-casing, the combination of a cap therefor, a reciprocating valve held against rotation, a threaded stem for operating the same, a compressor threaded upon said stem and held against rotation, a packing-block surrounding said stem and expanded into contact with said stem and cap in the reciprocation of said compressor, and a spring interposed between said packing and compressor; substantially as specified.

3. In a valve-casing provided with a vertical way, the combination of a valve-holder having wings operating in said way and interiorly threaded, an independent interiorly-threaded compressor provided with wings traveling in said way, a threaded stem passing through said compressor and entering said valve-holder, a compressible conical packing-block surrounding said stem above said compressor, a spring interposed between said packing and compressor, and a cap fitting said packing and secured to said valve-casing; substantially as specified.

In testimony whereof we affix our signatures in presence of two witnesses.

JAMES M. CARRICO.
WILLIAM G. CARRICO.
